UNITED STATES PATENT OFFICE.

HENRY HOWARD, OF CLEVELAND, OHIO, ASSIGNOR TO THE GRASSELLI CHEMICAL COMPANY, OF CLEVELAND, OHIO, A CORPORATION OF OHIO.

PROCESS FOR THE PRODUCTION OF HYDROGEN SULPHIDE.

No Drawing.

Application filed October 20, 1921. Serial No. 509,216.

To all whom it may concern:

Be it known that I, HENRY HOWARD, a citizen of the United States, residing at Cleveland, in the county of Cuyahoga and 5 State of Ohio, have invented certain new and useful Improvements in Processes for the Production of Hydrogen Sulphide, of which the following is a specification.

This invention relates to the production 10 of hydrogen sulphide, the process being particularly adapted to the production of hydrogen sulphide in large quantities for commercial purposes in which a simple continuous process, the use of cheap reagents and 15 high yields are essential. The process may of course be used for the production of hydrogen sulphide on a small scale, for instance, for laboratory use, if desired.

The process broadly consists in treating a 20 metal sulphide, such as zinc sulphide and more particularly a zinc sulphide ore with sulfuric acid whereby hydrogen sulphide is generated according to the following reaction.

The ordinary commercial method of generating hydrogen sulphide is by the treatment of iron sulphide with sulfuric acid. 30 This process is satisfactory for the production of small quantities of hydrogen sulphide, for instance, for use in chemical laboratories and in the de-arsenication of sulfuric acid, but when considerable quantities of hydrogen sulphide are required the 35 cost of the process is prohibitive.

It has been proposed according to the so-called Christensen process to treat complex sulphide ores containing zinc sulphide with 40 sulfuric acid. A feature of this process is the use of a relatively large quantity of sulfuric acid that is, about 50 pounds of 52° B. sulfuric acid to one pound of ore. With this ratio of acid to ore and at high temperature 45 the zinc sulfate formed is dissolved in the large excess of acid from which it is separated and recovered by cooling and crystallization.

The use of a large volume of sulfuric acid 50 in the so-called Christensen process is to enable the zinc sulfate to be brought into solution as it forms, the theory being that if it were not so dissolved it would form a coating over the ore and thereby prevent further reaction. The process is not a com-

mercial success owing to the enormous volumes of sulfuric acid required to be handled and the very expensive heat interchangers necessary for heating and cooling the same.

I have based my process upon the theory 60 that if the sulphide ore were ground sufficiently fine and then kept agitated in admixture with the acid, the reaction could be carried to substantial completion without dissolving the zinc sulfate formed in the re- 65 action.

My process is carried out as follows:

Sulfuric acid of about 52° B. is run into a lead-lined tank provided with a tight cover and efficient stirring means. The acid 70 is heated to about 190° C. and pulverized zinc sulphide ore is slowly fed in by means of an automatic and continuous feeding device, the contents of the tank being continuously stirred. The decomposition is 75 almost instantaneous producing a steady and continuous evolution of hydrogen sulphide the flow of which is controlled by controlling the feed of ore.

As stated above the ore must be finely 80 ground. I have tried the use of ore that would all pass through a 200 mesh screen and have thereby obtained a yield of from 80 to 85 per cent of hydrogen sulphide calculated upon the sulfur content of the ore 85 while 97% of the zinc sulphide content of the ore was converted into zinc sulfate. The loss of hydrogen sulphide has been found to be due largely to the formation of elemental sulfur. 90

About five pounds of sulfuric acid are used for one pound of ore rich in sulphides. It will be understood however that the ratio of acid to ore may be varied within a considerable range without departing from 95 my invention. It is only necessary to use sufficient acid to cause the reaction to proceed to substantial completion and the amount of acid required for any particular ore may be easily determined. 100

After the requisite amount of ore has been fed in to a batch of acid the stirring is continued and the mixture boiled until evolution of hydrogen sulphide is complete, whereupon the stirrer is stopped and the 105 batch cooled and allowed to settle. The supernatant acid which is still about 52° B. is siphoned off and mixed with fresh acid and used again for the treatment of another batch of ore. The acid thus recovered and 110

reused amounts to about one-half of the quantity used in each batch operation.

The slurry remaining in the bottom of the tank after the supernatant acid has been separated contains undissolved residue, zinc sulfate and free sulfuric acid. The sulfuric acid is separated on a sand filter and added to that siphoned off, for use in the next batch.

10 The filter cake is then treated with water sufficient to dissolve the zinc sulfate, the solution is neutralized by the addition of zinc oxide or zinc cinder and the zinc sulfate solution after separation from the undissolved residue, and purification in the ordinary well known manner, is available for use or sale as may be desired.

It will be seen that by my process hydrogen sulphide is cheaply and efficiently produced, in large quantities if desired, and that in the recovery of the zinc content of the ore the cost of the customary roasting of the ore and the loss of zinc resulting from the formation of ferrites and silicates 25 which are insoluble in acid are obviated.

I claim:

1. Process for the production of hydrogen sulphide which comprises, mixing zinc sulphide with sulfuric acid in quantity insufficient to dissolve all of the zinc sulfate formed by the interaction of the zinc sulphide with the sulfuric acid, and agitating and heating the mixture.

2. Process for the production of hydrogen sulphide which comprises, heating and agitating a mixture of pulverized zinc sulphide ore with sulfuric acid whereby hydrogen sulphide is evolved and zinc sulfate is formed, the sulfuric acid in said mixture 40 being insufficient to dissolve all of said zinc sulfate.

3. Process for the production of hydrogen sulphide which comprises, heating a body of sulfuric acid, feeding pulverized zinc sulphide ore into said acid with continuous agitation of the resulting mixture, and con-

tinuing the agitation and heating of said mixture until evolution of hydrogen sulphide substantially ceases.

4. Process for the production of hydrogen sulphide which comprises, mixing sulfuric acid with pulverized zinc sulphide ore in approximately the ratio of 5 parts by weight of acid to 1 part by weight of ore, heating and agitating the mixture until the evolution of hydrogen sulphide substantially ceases, separating sulfuric acid from the resulting slurry, and mixing said separated acid with a further quantity of zinc sulphide ore in a succeeding repetition of the process.

5. Process for the production of hydrogen sulphide which comprises, heating a body of sulfuric acid of about 52° Bé. to a temperature of 190° C., and while maintaining said temperature feeding zinc sulphide ore pulverized to pass a 200 mesh screen into said body of sulfuric acid with continuous agitation until one part by weight of ore to 5 parts by weight of said body of acid 70 has been fed in, heating and agitating the mixture, separating sulfuric acid from the resulting slurry, mixing said separated acid with fresh acid, and feeding pulverized zinc sulphide ore into said mixed acid in a succeeding repetition of the process.

6. Process for the production of hydrogen sulphide which comprises, mixing zinc sulphide ore pulverized to 200 mesh with sulfuric acid of 52° Bé., and heating and agitating the mixture.

7. Process for the production of hydrogen sulphide which comprises, mixing one part by weight of zinc sulphide ore pulverized to 200 mesh with 5 parts by weight of sulfuric acid of 52° Bé. at a temperature of 190° C., and heating and agitating the mixture.

In testimony whereof, I affix my signature.

HENRY HOWARD.
